US0D1006548S

(12) **United States Design Patent** (10) Patent No.: **US D1,006,548 S**
(45) Date of Patent: ** Dec. 5, 2023

(54) **BACKPACK COOLER**

(71) Applicant: **YETI Coolers, LLC**, Austin, TX (US)

(72) Inventors: **Jeffrey Charles Munie**, Austin, TX (US); **Kyle Edward Rogers**, Austin, TX (US); **Donald Edward Desroches**, Austin, TX (US); **John Loudenslager**, Austin, TX (US); **Derek G. Sullivan**, Austin, TX (US); **Alex Baires**, Austin, TX (US)

(73) Assignee: **YETI Coolers, LLC**, Austin, TX (US)

(**) Term: **15 Years**

(21) Appl. No.: **29/856,531**

(22) Filed: **Oct. 14, 2022**

Related U.S. Application Data

(63) Continuation of application No. 29/801,966, filed on Aug. 2, 2021, now Pat. No. Des. 970,299, which is a (Continued)

(57) **CLAIM**

The ornamental design for a backpack cooler, as shown and described.

DESCRIPTION

FIG. 1 is a top, front, right perspective view of a backpack cooler showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, rear, left perspective view thereof.

The broken lines immediately adjacent to the shaded area represent unclaimed boundaries of the design. The broken lines showing the remainder of the backpack cooler represent unclaimed subject matter.

1 Claim, 8 Drawing Sheets
